UNITED STATES PATENT OFFICE.

FREDERICK CRAIB, OF MARTINEZ, CALIFORNIA.

WRINGER MOP.

Application filed September 26, 1925. Serial No. 58,865.

To all whom it may concern:

Be it known that I, FREDERICK CRAIB, a citizen of the United States, residing in the city of Martinez and county of Contra Costa and State of California, have invented a new and useful Improvement in a Wringer Mop, of which the following is a specification.

My invention relates to improvements in wringer-mops wherein a pair of rollers, one of which is detachably mounted, are rotatably mounted upon one end of a suitable handle and operate to wring a mop-cloth mounted therebetween for the purpose 15 of wringing the water from said mop cloth.

The primary object of the present invention is to provide a new and improved wringer-mop having improved and simplified means incorporated therewith for 20 wringing the water or other fluid from the mop cloth.

Another object is to provide a new and improved wringer-mop of the character described which may be used in the mopping 25 process on either side or end of the mop-cloth thereof;

A further object is to provide improved and simplified means attached directly to a mop for detachably retaining and wringing the mop cloth thereof and of rendering said mop cloth instantly available for immediate use directly after it has passed in either direction through said wringer.

A further object is to provide a new and improved wringer-mop of the character described having a mop cloth which may be of any length and whose ends are provided with means for preventing said ends from passing through the wringer rollers during 40 the wringing process.

I accomplish these and other objects by means of the preferred form of construction disclosed in the drawings forming a part of the present specification wherein like characters of reference are used to designate similar parts throughout the said specification and drawings, and in which—

Fig. 1 is a broken front elevation disclosing my improved construction for a 50 wringer-mop;

Fig. 2 is a side elevation of Fig. 1;

Figs. 3, 4 and 5 are enlarged broken detailed views of the means for detachably retaining one of the rollers of the mop.

Referring to the drawings the numeral 55 1 is used to designate a suitable handle

having a suitable frame 2 secured to one end thereof, said frame 2 terminating in a pair of parallel arms or extensions 3 each provided with a bearing aperture 4 and a longitudinally disposed open ended slot 6 in the outer end thereof.

Rotatably mounted within the bearing apertures 4 of each arm 3 is a main roller 7, and slidably, detachably and rotatably mounted within the slots 6 is a second roller 8. In order to detachably and normally retain the roller 8 in engaging relation with the roller 7 I have provided slidable latches 9, slidably mounted upon the outer side of the arms 3 of the frame 2 and having laterally and inwardly extending extensions 10 apertured to slidably engage headed pins 11 rigidly mounted in the frame 2. Suitable springs 12 are interposed between the said frame 2 and the lateral extensions 10, the purpose of which will hereinafter be more fully set forth.

The end opposite the lateral extension of each latch 9 is provided with a circular aperture 14, arranged to permit the passage of an enlarged head 16 on the shaft or axle 17 of the roller 8, having a reduced extension or slot 18 arranged to rotatably engage said shaft or axle 17 and to prevent the passage of said enlarged head 16 thereof, whereby said enlarged head may serve as a retainer to detachably retain the lower ends of the latches 9 adjacent the arms 3 of the frame 2, the lower ends of the extensions or slots 18 are pulled upwardly by the tension of the springs 12 to cause the lower ends of the extensions of slots 18 to engage the axle or shaft 17 of the roller 8 and engaging relation with the roller 7, in order to permit a sliding movement of the said latches 9 slots 19 are provided which engage the shaft 21 of the roller 7 and also with a similar slot 22 through which passes one end of a crank 23 rotatably mounted within the frame 2 and arranged at such an angle with the roller 7, as shown in Fig. 1 of the drawings, as to prevent interference of said crank 23 with the full use of the mop during the mopping process. One end of the crank 23 is provided with a pinion 26 which meshes with a gear 27 on the roller 7 whereby rotation of the crank 23 will rotate the rollers 7 and 8.

Detachably mounted between the rollers 7 and 8 is a mop cloth 28 said mop cloth 28 having its ends turned back upon said cloth

and stitched thereon to provide a double thickness of said cloth immediately adjacent the ends thereof to prevent passage of said ends through the rollers 7 and 8.

- 5   In operation the mop cloth 28 is dipped within a bucket of cleansing liquid, not shown, and is wrung by rotating the crank 23 which in turn rotates the rollers 7 and 8 through the pinion 26 and gear 27.
- 10   The compression of the springs 12 operate to normally and resiliently retain the roller 8 in engaging relation with the roller 7 and inasmuch as the mop cloth 28 is mounted between the said rollers it is obvious that 15 rotation of the rollers 7 and 8 will pass the mop cloth 28 between said rollers and squeeze or wring the liquid or fluid therefrom. As the rollers 7 and 8 are rotated as above described the mop cloth is passed 20 under pressure between said rollers until the double thickness immediately adjacent the ends of said mop cloth approaches the space between said rollers. By reason of this 25 double thickness of the mop cloth the ends of the same are prevented from passing between the rollers 7 and 8. The mop is now available for use in mopping the floor or other surface. When the next successive 30 wringing operation is required, the direction of rotation of the crank 23 is reversed and the mop cloth 28 is wrung while being passed between or through the rollers in the opposite direction and until the opposite end of said mop cloth 28 with its double thickness 35 approaches the rollers 7 and 8, when the mop is again available for immediate use without any other or additional operation.

It is obvious from the foregoing that the

mop may be easily and readily wrung without touching the mop cloth with the hands, and is also immediately available for use after having been wrung through the rollers in either direction and may be wrung by passing said mop cloth in either direction. 40 45

Having thus described my invention what I claim as new and desire to secure by Letters Patent is—

A wringer-mop comprising a handle; a frame mounted upon one end of said handle; a roller rotatably mounted within said frame; a gear mounted upon one end of said roller; a crank rotatably mounted within said frame and at an angle to said roller to prevent interference of said crank with a 50 mopping process of said mop; a pinion mounted upon one end of said crank and engaging the gear upon the roller whereby said roller may be rotated when said crank is rotated; a second roller rotatably, 55 detachably and slidably mounted within said frame and adjacent and parallel to the first mentioned roller; latches slidably mounted upon the sides of the frame and detachably engaging the ends of the second mentioned roller; resilient means for moving the slideable latches to normally retain the second mentioned roller in engaging relation with the first mentioned roller; and a mop cloth 60 detachably mounted between the rollers and having the ends of said mop cloth turned back and secured to the body of said cloth to provide a double thickness at said ends to prevent passage of said ends through said rollers. 65 70 75

In witness whereof I have hereunto set my signature.

FREDERICK CRAIB.
